UNITED STATES PATENT OFFICE.

ROBERT HOADLEY, OF ANSONIA, CONNECTICUT, ASSIGNOR TO THE ANSONIA
BRASS AND COPPER COMPANY, OF SAME PLACE, AND WOLCOTT A.
HULL, OF NEW YORK, N. Y.

MANUFACTURE OF ARTICLES OF SHEET METAL FOR LAMP-FIXTURES.

SPECIFICATION forming part of Letters Patent No. 311,321, dated January 27, 1885.

Application filed June 12, 1884. (No model.)

To all whom it may concern:

Be it known that I, ROBERT HOADLEY, of Ansonia, in the county of New Haven and State of Connecticut, have invented a certain 5 new and useful Improvement in the Manufacture of Articles of Sheet Metal for Lamp Fixtures, of which the following is a specification.

The object of this improvement is to facilitate the manufacture of articles of sheet metal 10 such as are used in lamp-fixtures and are ornamented with embossed panels.

I will describe the improvement in detail, and then point out its various features in the claim.

15 In the accompanying drawings, Figure 1 is a side view of a press furnished with dies for carrying out my improvement. Fig. 2 is a sectional elevation of the dies on a larger scale. Fig. 3 is a partly-sectional front view 20 of the dies on the same scale as Fig. 2. Fig. 4 is a face view of the male die on the same scale as Fig. 2. Fig. 5 is a face view of the female die on the same scale as Fig. 2. Fig. 6 is a face view of a blank to be treated by 25 the dies, and on the same scale as Fig. 2; and Fig. 7 is a face view of an article treated by the dies, and on the same scale as Fig. 2.

Similar letters of reference designate corresponding parts in all the figures.

30 A designates a press, which may be of any suitable form. It will preferably be operated by steam or analogous power. The male die B is stationary while in use. It is supported in a rest, C, which is erected on a table, D, 35 secured to the frame of the press in such manner that it may be moved up or down. The rest C extends upwards obliquely to the height of the press. The shank of the male die B passes through the rest C, and is secured there- 40 in by a nut, E, applied to its rear end. It will be observed that the male die is arranged so that its axis extends obliquely to the height of the press. In shape the male die is approximately hemispherical in the present example of my invention. It has, however, at the inner end an enlarged cylindrical portion, a. At the uppermost portion it has a seg- 45 mental portion bounded by radial grooves b

and arc-shaped grooves b', crossed by intersecting grooves b'', leaving isolated portions 50 b'', which, as here shown, are of such shape and disposition as to represent the configuration of alligator-skin. The female die F has a concave face, c, which has ribs d d' d'', corresponding to the grooves b b' b'' of the male die, 55 and recesses d'', corresponding to the portions b'' of the male die. It is not material what the external contour of the female die shall be. As here shown it is of rectangular bar form. This die, as here shown, has a dovetail shank, which 60 is fitted into a dovetail groove in a holder, G, and secured there by a key, H, driven in between it and the holder. The holder G is secured to the plunger e of the press by a set-screw or other means passing through the 65 plunger and acting against the shank of the holder.

Projecting from the rest C, close to the side of the male die B, is a gage, I, consisting of a narrow rod or finger. This gage, as here 70 shown, is secured in place by screws f, and tapers to a point. It will preferably be made of metal.

J designates a sheet-metal shell conforming in shape to the exterior of the male die. It is 75 temporarily fastened to the male die by a screw, g, passing through it and entering the male die. It is not clamped tightly to the male die by this screw, but is only fastened thereto loosely, so that it may be rotated by 80 the operator upon the male die. The press is started, its plunger descends, and the shell J is stamped by the dies. Thus a segmental portion will be stamped, so as to produce a surface corresponding to the surfaces of the 85 dies. It will then have in the exterior of this segmental portion grooves h h' h'', corresponding to the grooves b b' b'' of the male die, and portions h'', corresponding to the portions b'' of the male die. After the plunger has been 90 raised the operator turns or rotates the shell J upon the male die till the nearer of the two grooves h comes in line with one of the sides of the gage I. If necessary, he may stop the press to afford him sufficient time for thus ad- 95 justing the shell. After the adjustment of the

male die the plunger is caused to descend again, whereupon another segmental portion of the shell will be stamped. These operations are repeated until the shell is stamped all around the circumference. When finished, the shell will have the appearance represented in Fig. 7. It will then have a number of segmental portions separated by rib-like portions. The shell J is now removed and another is arranged in its place.

By my improvement I am enabled to stamp the shell in panels, so as to have the panels meet properly all around the circumference of the shell. The portions h^3 strengthen the shell in various directions, and the intervening rib-like portions, i , will strengthen the shell in radial directions, or, in other words, from the central portion to the edge. The appearance of the shell will also be highly ornamental.

What I claim as my invention, and desire 20 to secure by Letters Patent, is—

The process of stamping a sheet-metal shell consisting in stamping a segmental portion, in turning the shell a certain distance, in then stamping another segmental portion, leaving an intervening rib-like portion between it and the first stamped segmental portion, and in proceeding similarly until the shell is stamped entirely around its circumference with segmental portions having intervening 30 rib-like portions between them, substantially as specified.

ROBERT HOADLEY.
